his Attorney.

UNITED STATES PATENT OFFICE.

ROBERT GOLDSTEIN, OF PITTSBURG, PENNSYLVANIA, ASSIGNOR OF ONE-HALF TO WOODWORTH, EVANS & COMPANY, OF SAME PLACE.

CURTAIN-HOLDER.

SPECIFICATION forming part of Letters Patent No. 668,289, dated February 19, 1901.

Application filed March 24, 1900. Serial No. 9,988. (No model.)

To all whom it may concern:

Be it known that I, ROBERT GOLDSTEIN, a resident of Pittsburg, in the county of Allegheny and State of Pennsylvania, have 5 invented a new and useful Improvement in Curtain-Holders; and I do hereby declare the following to be a full, clear, and exact description thereof.

My invention relates to curtain-fixtures, 10 and has for one object to provide a cheap and simple fixture which can be applied to the opposite sides of any window for supporting the curtains thereon, as well as permitting the fixtures and curtains to be removed from the 15 windows at any time desired by a person standing on the floor for the purpose of removing or changing the curtains from the fixtures, the cleaning of the window-frame, and other purposes.

20 A further object of my invention is to provide such a form of curtain-pole fixture as will be permitted to swing outward from the window in order that such window can be cleaned or washed without taking down the 25 curtains and other purposes, as desired; and a still further object is to provide such a fixture whereby draperies can be hung thereon without interfering with the curtains, as well as allowing the shades or blinds to be freely 30 operated at all times.

My invention consists, generally stated, in the novel arrangement, construction, and combination of parts, as hereinafter more specifically set forth and described, and particularly pointed out in the claims.

To enable others skilled in the art to which my invention appertains to construct and use the fixture, I will describe the same more fully, referring to the accompanying sheet of drawings, in which—

Figure 1 is a face view of a window and frame, showing two of my improved curtain-pole fixtures applied thereto and one of said fixtures being swung or projected outward 45 from said window. Fig. 2 is a side view of such window-frame shown in Fig. 1. Fig. 3 is a top view of the fixture applied to the frame and showing some of the parts in section. Figs. 4 and 5 are perspective views of 50 the parts for attaching the fixture to the

frame. Figs. 6 and 7 are views showing another manner of attaching the fixture at the upper end to the frame.

Like numerals herein indicate like parts in each of the figures of the drawings.

As illustrated in the drawings, 1 represents the window-frame, 2 the sides thereof, and 3 the top of the frame, and within said frame 1 the shade or blind 4 is journaled or mounted in brackets 5, secured to the sides 2 of said frame by the extensions 6 thereon. Inclined or wedge-shaped grooves 7 are formed in the extensions 6, within which are adapted to fit inclined or wedge-shaped tongues 8, formed on the sides of the curved slides 9, and brackets 10 are secured to the sides 2 of the frame 1 at the lower end thereof, which are provided with inclined or wedge-shaped grooves 11 therein for the reception of inclined or wedge-shaped tongues 12, formed on the sides 6 of the curved slides 13. Curved seats 9' and 13' are formed in the slides 9 and 13 for the reception of the curtain-poles 14, which are preferably formed of wire, having the vertical portions 15, handle portions 16 extending out 60 therefrom at their lower ends, and the horizontal portions 17, having the inwardly-extending portions 18 and 19 thereon, the portions 18 being connected to the vertical portions 15 at their upper ends. The portions 15 of the poles 14 are held in place within the seats 9' of the slides 9 by means of pins 20, secured in said portions 15 and engaging with curved slots 21, formed in the slides 9, and the portions 15 are also held within the seats 85 13' of the slides 13 by means of thumb-screws 22, pressing through said slides 13 and engaging with the portions 15 on the poles 14.

The use and operation of my improved curtain-fixture are as follows: After the curtain has been placed around the horizontal portion 17 of one of the poles 14 and around the portion 19 thereof, if desired, the pole 14 is raised to position and the slide 9 around the portion 15 of the same is wedged into place 90 by pulling down on the pole 14 and inserting the inclined tongues 8 within the inclined grooves 7 in the extensions 6 of the brackets 5. The slide 13 can then be placed around the portion 15 of the pole 14 by inserting the 95 100

portion 15 within the seat 13' and sliding the same along until the inclined tongues 12 thereon are wedged within the inclined grooves 11 on the brackets 10, after which 5 the pole 14 can be turned by means of the handle portion 16, so that the inwardly-extending portion 19 thereon comes in contact with the top 3 of the frame 1, when the thumb-screw 22 can be screwed down against the 10 portion 15 to lock the pole 14 in place, as shown to the right of Fig. 1. The other curtain-pole 14 can also be placed in position in like manner, and when it is desired to swing out the curtains for the purpose of cleaning 15 the window or any other purpose all that is necessary is to unscrew the thumb-screws 22, so that the portions 15 on the poles 14 will be free to turn within their seats 9' and 13' in the slides 9 and 13, when the operator can 20 grasp the handle portions 16 on the poles 14 and throw the same outward, which will cause the poles 14 and curtains thereon to be projected outward, as shown to the left of Fig. 1, the vertical portion 15 on the poles 14 being 25 adapted to turn within the seats 9' and 13' in the slides 9 and 13, and the pins 20 being adapted to travel within the curved slots 21 on the slides 9.

When it is desired to take down the curtain-poles 14 and curtains thereon for the purpose of repairing, cleaning the same, or any other purpose, all that is necessary is to unscrew the screws 22 and push upon the poles 14 by means of the handles 16 thereon, which 30 will cause the tongues 8 and 12 on the slides 9 and 13 to free themselves from the grooves 35 7 and 11 in the brackets 5 and 10, and so free the poles 14 therefrom and from the sides 2 of the frame 1, when such poles can be lifted 40 down and the curtains removed therefrom, as desired.

In Fig. 3 there is shown a device for use in case lambrequins are employed in connection with the curtains, and in such use a rod 23 45 extends across between the inwardly-extending portions 18 and 19 and passes through holes 18' and 19' therein, and a nut 23' engages with a threaded portion on said rod 23 adjacent to the portion 18 for removing the 50 end of said rod 23 from the hole 18' when desired. This construction permits the curtain to be placed around the rod 23 and the lambrequin around the horizontal portion 17 of the pole 14 when the device is used, so that 55 the lambrequin will appear on the outside of the curtain and both be placed in position on the frame 1, swing out therefrom, and removed from the same as desired.

In Figs. 6 and 7 another device for attaching 60 the pole 14 at the upper end of the portion 15 is shown, which consists of providing a separate bracket 24 from the bracket 5 of the shade or blind 4, and this bracket 24 being provided with a flap 25' to form a curved 65 slot 25 thereon for the reception of the portion 15 of the pole. The flap 25' terminates

in a spring-lip 26 to enable the portion 15 to be sprung into the slot 25 and be held therein by such flap 25'.

It will of course be understood that while 70 two curtain-fixtures are shown and described in connection with a single window-frame for a pair of curtains and lambrequins, any one of such fixtures can be used in connection with one window for holding single or double 75 curtains or lambrequins if desired, and it will also be evident that various modifications in the construction and design of the various parts of the fixtures may be resorted to without departing from the spirit of the invention 80 or sacrificing any of its advantages.

What I claim as my invention, and desire to secure by Letters Patent, is—

1. In a curtain - fixture, the combination with the window-frame provided with brackets thereon, of a pole for carrying the curtain, and wedge-plates fitting around said pole and adapted to engage with the brackets on said frame for permitting said pole to be removably secured to and be swung to and from 90 said frame.

2. In a curtain - fixture, the combination with the window-frame provided with brackets thereon, of a pole for carrying the curtain and provided with a vertical portion thereon, 95 wedge-plates fitting around said vertical portion and adapted to engage with the brackets on said frame for permitting the pole to be removably secured to and be swung to and from said frame, and means for securing said 100 wedge-plates in position on the vertical portion of the pole.

3. In a curtain - fixture, the combination with the window-frame provided with brackets thereon, of a pole for carrying the curtain 105 and provided with a vertical portion thereon, upper and lower wedge-plates fitting around said vertical portion and adapted to engage with the brackets on said frame for permitting the pole to be removably secured to and be swung to and from said frame, said upper 110 wedge-plate having a slot therein, and a pin on said vertical portion adapted to engage with the slot in the upper wedge-plate to hold the pole in position.

4. In a curtain - fixture, the combination with the window-frame provided with brackets thereon, of a pole for carrying the curtain and provided with a vertical portion thereon, wedge-plates fitting around said vertical portion 115 and adapted to engage with the brackets on said frame for permitting the pole to be removably secured to and be swung to and from said frame, and a thumb-screw on the lower wedge-plate adapted to engage with 120 said vertical portion for locking the pole in position.

5. In a curtain - fixture, the combination with the window-frame, of a pole having a vertical portion thereon, means on said frame 130 connected to said vertical portion for permitting the latter to be removably secured to and

be swung to and from said frame, a horizontal portion, an inwardly-extending portion connected at one end to the horizontal portion and at the other to the upper end of the vertical portion, an inwardly-extending portion at the opposite end of the horizontal portion, said inwardly-extending portions provided with openings therein, a rod engaging with

5 said openings, and a nut engaging with said rod.

In testimony whereof I, the said ROBERT GOLDSTEIN, have hereunto set my hand.

ROBERT GOLDSTEIN.
